(57) **CLAIM**

The ornamental design for a notebook laptop computer, as shown and described.

DESCRIPTION

1. Notebook Laptop Computer

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

The broken lines indicate portions of the article that form no part of the claimed design; reproductions 1.1 to 1.7 show the closed state, and reproductions 1.8 to 1.14 show the opened state. The dark circles seen in reproductions 1.4, 1.5 and 1.7 are groupings of holes.

1 Claim, 14 Drawing Sheets(56)
